US00D612491S

(12) **United States Design Patent**
Sullivan Conrad et al.

(10) **Patent No.:** **US D612,491 S**
(45) **Date of Patent:** **** Mar. 23, 2010**

(54) **PRINTED ABSORBENT ARTICLE**

(75) Inventors: **Suzanne K. Sullivan Conrad,**
Combined Locks, WI (US); **Jane B. Kelly,** Neenah, WI (US); **Mary L. McDaniel,** Appleton, WI (US);
MaryAnn Zunker, Oshkosh, WI (US)

(73) Assignee: **Kimberly-Clark Worldwide, Inc.,**
Neenah, WI (US)

(**) Term: **14 Years**

(21) Appl. No.: **29/285,501**

(22) Filed: **Mar. 30, 2007**

(51) **LOC (9) Cl. 24-04**

(52) **U.S. Cl. D24/124**

(58) **Field of Classification Search** D24/124-125;
604/385.07, 358, 363, 364, 368-375, 385.01,
604/385.03, 385.14, 385.23, 387, 390; D5/37-43,
D5/53, 56, 57, 58, 60-62

See application file for complete search history.

(57) **CLAIM**

We claim the ornamental design for the printed absorbent article, as shown and described.

DESCRIPTION

FIG. 1 is a front view of a printed absorbent article, showing our new design; and,

FIG. 2 is a front view thereof, with alternate shading to show color contrast.

The broken line showing of the outer portion of the absorbent article is for illustrative purposes only and forms no part of the claimed design.

1 Claim, 2 Drawing Sheets
